RALPH N. RICHARDS, OF TOLEDO, OHIO, ASSIGNOR TO OTTAWA RIVER PAPER COMPANY, OF TOLEDO, OHIO, A CORPORATION OF OHIO

DEVICE FOR CATCHING AND STACKING SHEET MATERIAL

Application filed September 29, 1930. Serial No. 485,053.

This invention relates to the stacking of sheets of material as they are delivered from a machine, as for example, corrugated paper, pasted board or other sheet material, which, after having passed through the cutting device or other machinery in rapid succession, is delivered to a receiving table. In modern manufacturing plants, these sheets when delivered for stacking are travelling 100 to 1000 feet per minute. It is the object of the present invention to provide means for stacking sheets uniformly upon a receiving table, and particularly to perform such stacking operation without injuring the edges of the sheets in any way. The invention includes means for adjusting the receiving table for sheets of various sizes and the operation of the stacking means is entirely automatic.

The invention will be more particularly described in connection with the accompanying drawings, in which

Figure 1 is a side elevation of the invention with parts broken away.

Figure 2 is a plan view of the same.

Figure 3 is a section taken substantially on the line 3-3 of Figure 1.

Figure 4 is a section taken substantially on the line 4-4 of Figure 1.

Figure 5 is a sectional view of one of the side stops taken substantially on the line 5-5 of Figure 1.

Figure 6 is a view of the side stop looking from the right of Figure 5.

The invention is adapted to be used in connection with process machinery or delivery mechanism supported by a frame 8. Such delivery mechanism may include a conveyor made up of one or more endless belts 9 passing about drums 10 and 11 which are mounted on shafts 12 and 13, respectively. These shafts 12 and 13 are journaled in the frame 8 and one of them may be extended beyond the side of the conveyor 9 and connected with suitable drive mechanism.

The sheet material is received and carried forwardly by the conveyor 9, or dropped directly to a receiving table 14 which is located at the delivery end and somewhat below the surface of the conveyor. The surface of the

table 14 is preferably made up of spaced longitudinal slats 15. The outer end of the table is supported by legs 16 provided with suitable braces 42 and having rollers or casters 17 at their lower ends. The table 14 also has longitudinal side bars 18 which are slidably mounted between guide rails 19, secured to the frame 8, so that the table may be adjusted longitudinally. For effecting such adjustment, a rack bar 20 is secured beneath the top of the table and is adapted to be moved outwardly or inwardly by means of gears 21 actuated by a hand wheel 22 located at one side of the frame 8. A scale 23 may be provided on the side edge of the table to indicate the length of the sheets which the table is adjusted to receive.

The means for stacking the sheets with their edges arranged uniformly comprises stop fingers 24 secured to guide rails 19 at the delivery end of the conveyor 9 and adapted to engage the rear edges of the sheets, and an opposed stop member 25 pivotally connected at 26 to the legs 16 at the outer end of the receiving table. The stop member 25 preferably includes fingers which project upwardly between the slats 15 and are normally held in abutting relation to a transverse bar 27 of the table by means of a spring 28 connected at one end to an arm 29 projecting from the stop member and connected at its other end to an intermediate point on a transverse rod or bar 41 connecting the legs 16. The arm 29 is preferably arcuate in shape and provided with a series of notches with which the spring 28 may be selectively engaged to vary its effect on the yieldable stop.

As the sheets are delivered from the rapidly traveling conveyor 9 their front edges strike the stop 25 which yields sufficiently to prevent injury to the sheets and also to allow free movement of the rear edges of the sheets downwardly over the rear stop 24. The yieldable stop 25 is immediately returned into abutting relation to the bar 27 and thus moves each successive sheet backwardly against the stop 24. It is understood, of course, that the extension of the table has been previously adjusted to the length of the

sheets being delivered. As fast as the sheets are stacked upon the table 14 they are removed by one or two attendants. The table is usually provided with lateral wings 40 to assist in removing the sheets.

In addition to the stops 24 and 25 for the front and rear edges of the sheets, it may also be expedient to provide side stops 30 for lining up the side edges of the sheets. Each of these side stops 30 is adjustably supported in a keeper 31 by means of a rack bar 32 which may be adjusted inwardly or outwardly of the keeper by means of a pinion 33 in engagement with the rack bar and secured to a shaft 34 which extends outwardly of the keeper and is provided with a knob 35 or other means for rotating it. The keeper 31 may be adjusted longitudinally of the table and secured to one of the slats 15 by means of a cleat 36 secured to the bottom of the keeper and a cam 37 which cooperates with the cleat 36 to clamp the keeper to the slat at any point along the length of the table. The cam 37 is secured to a spindle 38 which extends through the wall of the keeper and is provided with a handle 39 for rotating the same.

From the foregoing description it will be seen that I have provided means for stacking the sheets automatically as they are delivered from the conveyor or process machinery and that the stacking device may be adjusted for sheets of any length or width. The sheets may thus be handled most advantageously and the edges of the same will not be injured. The device is particularly adapted for use with modern high speed machinery.

While I have shown and described specifically the preferred form of the invention, it is apparent that the same may be considerably modified without departing materially from the scope of the invention as claimed.

What I claim is:

1. A table for receiving and stacking sheets and provided with spaced stops for engaging the ends of the sheets, a pair of side stops, and means for selectively securing said side stops to the table in opposed relation to each other and at different distances apart to accord with the width of the sheets delivered from the conveyor.

2. A table for receiving and stacking sheets of material and comprising longitudinally disposed spaced slats, spaced stops for engaging the ends of the sheets, a pair of side stops, means for selectively securing said side stops to said slats and in opposed relation to each other, and means for adjusting said side stops so that the distance between them will accord with the width of the sheets to be stacked.

3. A table for receiving and stacking sheets and comprising longitudinally disposed spaced slats, spaced stops for engaging the ends of the sheets, a pair of side stops,

keepers in which the side stops are mounted, means for selectively securing the keepers to the slats at various distances from the longitudinal center line of the table, and means for adjusting the side stops with reference to the keepers toward or away from said center line.

4. A table for receiving and stacking sheets and provided with two opposed stops adapted to engage opposite ends of the sheets delivered thereto, one stop being fixed, the other stop being carried by the table and disposed in the path of the sheets as they are delivered, and means including a rack and pinion for adjusting the table together with the last mentioned stop longitudinally to accord with the length of the sheets to be stacked.

5. A table for receiving and stacking sheets and provided with two opposed stops adapted to engage opposite ends of the sheets delivered thereto, one stop being fixed, the other stop being pivoted to the table and disposed in the path of the sheets as they are delivered, an abutment positively limiting the movement of the pivoted stop toward the stack, yieldable means for normally holding the pivoted stop against said abutment, and means including a rack and pinion for adjusting the table together with the last mentioned stop longitudinally to accord with the length of the sheets to be stacked.

6. In combination, a table for catching and receiving sheets of material, a horizontal endless conveyor above the plane of the table and in position to deliver the sheets over one end thereof, said table being provided with two opposed stops adapted to engage opposite ends of the sheet, the stop at the end over which the sheet is delivered to the table being fixed, a spring yieldably urging the other stop toward the delivery means in the path of the sheet as the latter is delivered to the table, an abutment limiting the movement of said other stop under the influence of the spring to a perpendicular position, and means for adjusting the tension of said spring to adapt it to sheets of different weight.

7. In combination, a table for receiving and stacking sheets of material, a horizontal endless conveyor above the plane of the table and in position to deliver sheets over one end thereof, said table being provided with two opposed stops adapted to engage opposite ends of the sheets delivered thereto, one stop being fixed to the table beneath the points where the sheets leave the conveyor, the other stop being pivoted to the table and projecting into the path of the sheets as they are projected from the conveyor, an abutment positively limiting the movement of the pivoted stop towards the stack, an arm projecting laterally from the pivoted stop, and yieldable means attachable to said arm

to hold the stop normally against said abutment, said yieldable means being selectively adjustable along said arm to vary the effective force with which the pivoted stop is held.

5 In testimony whereof I have hereunto signed my name to this specification.

RALPH N. RICHARDS.
